(57) **CLAIM**

The ornamental design for a chocolate dispenser, as shown and described.

DESCRIPTION

FIG. 1 is a top front right side perspective view of a chocolate dispenser showing my new design;

FIG. 2 is a bottom front right side perspective view of the chocolate dispenser of FIG. 1;

FIG. 3 is a top rear left side perspective view of the chocolate dispenser of FIG. 1;

FIG. 4 is a front elevation view of the embodiment of the chocolate dispenser of FIG. 1.

FIG. 5 is a right side elevation view of the embodiment of the chocolate dispenser of FIG. 1, with the left side elevation view being a mirror image of the same.

FIG. 6 is a rear elevation view of the embodiment of the chocolate dispenser of FIG. 1.

FIG. 7 is a top plan view of the chocolate dispenser of FIG. 1; and,

FIG. 8 is a bottom plan view of one end of the embodiment of the chocolate dispenser of FIG. 1.
